UNITED STATES PATENT OFFICE.

SAMUEL D. STYLES, OF NEW YORK, N. Y.

CALENDAR.

SPECIFICATION forming part of Letters Patent No. 289,167, dated November 27, 1883.

Application filed March 21, 1883. (No model.)

To all whom it may concern:

Be it known that I, SAMUEL D. STYLES, a citizen of the United States, residing in the city of New York, county of New York, and State of New York, have invented certain new and useful Improvements in Calendars, fully described and represented in the following specification and the accompanying drawings, forming a part of the same.

10 This invention relates to that class of calendars in which the days of the different months are indicated upon a series of leaves or sheets so arranged that by removing one of the sheets at the end of each month a new sheet will be 15 presented for the succeeding month, and so on to the end of the year, or other period for which the calendar is intended.

It is the object of the invention to produce a calendar of this general character which shall 20 not only present a neat and attractive appearance and afford a convenient and desirable advertising medium, but which shall also afford greater facilities for ascertaining the day of the week or month than have heretofore 25 been possessed by calendars of this character.

To these ends the invention consists in various details of construction, which will be hereinafter fully explained and particularly pointed out.

30 In the accompanying drawings, Figure 1 is a plan view of a calendar embodying the present invention, the upper or outer leaf of the series being partly torn away. Fig. 2 is a central transverse vertical section of the same.

35 Referring to said figures, it will be seen that the calendar is composed of a series of leaves or sheets, *a*, each of which bears at its top the name of one of the months of the year, and around its outer edge a row of figures or characters representing the days of said month. The 40 sheets *a* are secured together by means of one or more staples or other suitable fastening, *b*, which fastening, as shown in the present case, (which is the preferred construction,) also secures the sheets to a suitable card or backing, *c*. This backing, which affords a support for the calendar, may be provided with an easel-leg for supporting the calendar in an upright or inclined position upon a desk or table, or 45 with a suitable device, as *d*, for suspending it against the wall of a room.

It will usually be found most desirable to provide one of the leaves *a* for each month of the year. A greater or less number may, however, be used. Each of the leaves may represent only a part of a month, or each leaf 55 may bear figures representing the days of two or more months; and, if desired, a sufficient number of leaves may be provided to make the calendar available for more than one year. 60 The form of the leaves and backing is not essential. That shown, however, is deemed preferable.

The series of leaves *a*, arranged as just described, are provided with a hand or pointer, 65 *e*, mounted to turn upon a small stud or bolt, *f*, which passes through the center of the leaves and backing, and is provided with a nut, *g*, which can be advanced onto the stud, so as to hold the pointer snugly against the face of the 70 outer leaf. As the days succeed each other the pointer will be advanced step by step, so as to always indicate the proper day, and thus a person consulting the calendar will be enabled to ascertain the day of the month without 75 the trouble of careful scrutiny. At the end of the month the outer leaf will be torn off, so as to display the leaf for the next month, and the nut *g* will be slightly advanced, so as to hold the pointer snugly against the face of the new 80 leaf, and the operation will continue to be repeated until all of the leaves have been removed. The space upon the backing *c*, outside of the leaves *a*, may be provided with suitable ornamentation, as the border *h*, to 85 give the calendar an attractive appearance, or it may contain advertising matter, or other matter giving useful or desirable information. The back of the card *c* may also be utilized in the same manner. The figures or characters 90 indicating the days of the month may and preferably will be accompanied by the names of the days of the week, as shown, and the figures representing the Sundays will preferably be printed with a different style of type, as 95 also shown, or in a different color, or be otherwise made readily distinguishable. These features will add both to the convenience and attractiveness of the calendar. The space upon the leaves *a*, inside the row of figures representing the days of the month, may be provided with any suitable ornamentation; or it 100

may be utilized for advertising purposes. A portion of this space will preferably be occupied, as shown in the drawings, by a series of small tabular calendars for the months of the year. These small calendars will be found very useful as a means of reference to past or future dates.

By combining the pointer or index-finger with the series of removable leaves or sheets, the calendar just described is given all the desirable features of the more expensive and complicated structures heretofore in use, and at an expense very little in excess of the ordinary pad or tablet calendar.

15 What I claim is—

1. The combination, with the pointer *e* and its stud, of the series of leaves *a*, secured to each other at one or more points near their

edges, and having arranged around their edges a row of figures or characters indicating the 20 days of the month and made of fragile material, so as to be torn away one by one without disturbing said pointer or its stud, substantially as described.

2. The combination, with the series of leaves 25 *a*, of the pointer *e*, stud *f*, and nut *g*, whereby said pointer can be kept constantly pressed against the outer leaf as the number of leaves decreases, substantially as described.

In testimony whereof I have hereunto set 30 my hand in the presence of two subscribing witnesses.

SAML. D. STYLES.
